UNITED STATES PATENT OFFICE.

ANDREW E. OLSON, OF WATAGA, ILLINOIS.

SEED-CORN SHELLER.

Application filed February 7, 1921. Serial No. 442,939.

To all whom it may concern:

Be it known that I, ANDREW E. OLSON, a citizen of the United States, residing at Wataga, in the county of Knox and State of Illinois, have invented certain new and useful Improvements in Seed-Corn Shellers, of which the following is a specification.

My invention relates to corn shellers and consists in a plurality of roughened shelling 10 elements mounted in pairs upon a longitudinal frame adapted to be supported upon a barrel or box and to adjust cooperating shelling elements to and from each other.

My sheller is especially adapted for use 15 in shelling seed corn. In such use it is desirable to remove the defective grains which are present on the rounded butt and tip of each ear and one object of my invention is to provide shelling elements which will effectively remove such grains.

Another object of my invention is to provide a sheller in which different sized tips and butt ends of the ears may be shelled without readjustment of the shelling 25 elements.

Another object of my invention is to provide an arrangement of shelling elements so that not only the ends of the ears may be shelled but also the intermediate portions.

30 In the accompanying drawings illustrating my invention—

Fig. 1 is a plan of my complete sheller and

Fig. 2 is a vertical transverse section taken 35 on the line 2—2 of Fig. 1 and shown on an enlarged scale.

The frame of the sheller consists preferably of an angle iron having a portion of one flange cutaway intermediate its ends 40 and which is bent into U-shape at the cutaway portion. The shelling elements 1, 2, 3, and 4 are mounted in pairs along the legs 5 and 6 of the frame, one pair being located near the base of the U and the other pair being substantially spaced from the first 45 pair. The base of the frame tends to spring the two legs apart and a bolt 7 provided with a nut 8 is used to limit the movement of the legs from each other.

50 Each shelling element consists of a block having a tapered concave surface 9 and is

provided with frame attaching flanges 10. The surface 9 is roughened or provided with spaced teeth 11 which engage the grains and tear them from the cob. It will be noted 55 that the elements 1 and 2, 3 and 4 are positioned on the frame so as to present their toothed surfaces towards each other and when so assembled form a plurality of split conical cups with their axis at right angles 60 to the plane of the frame.

By tightening or loosening nut 8 on bolt 7 the opposed shelling elements are adjusted 65 towards and from each other thus providing means for accommodating unusual variations in the size of the ear to be shelled.

Each shelling element is provided with an exterior spur 12 adapted to shell out a single row of grains which are not desired.

As legs 5 and 6 are flexibly united at one 70 end of the frame, the space between elements 1 and 2 will vary from the space between elements 3 and 4 at all times except when the frame legs are parallel. Consequently there will always be two sizes of shelling 75 cups available without adjustment, one for shelling the tip and the other for shelling the butt of an ear of corn. By spacing the outer elements sufficiently, they may be used for shelling the body of the ear while, at the 80 same time, the inner shelling elements will be adapted for shelling the butt or tip of the ear.

The free ends of the members 5 and 6 of the frame constitute handles whereby the 85 frame members and the shelling elements may be adjusted toward and from each other.

It will be noted that the cooperating shell- 90 ing elements are positively limited in their movement from each other irrespective of the pressure applied by the workman. I consider this a more advantageous arrangement than the usual construction in which separation of similar elements is restricted 95 by a spring or springs.

My device is exceedingly simple and economical in construction as it consists of a length of angle iron, four simple castings or forgings and an ordinary bolt. It is adapt- 100 ed to be placed across a barrel or box and the shelled grains are delivered through the

frame to the receptacle. It is easily shifted from one receptacle to another or clamped thereon. I have shown and described a preferred embodiment of my invention, but I reserve the right to make therein any changes or modifications which fairly fall within the scope of the following claims.

I claim:

1. In a corn sheller, a frame comprising a pair of members flexibly connected at one end, the other end of said members constituting handles for moving the members toward each other, and a plurality of shelling cups spaced apart lengthwise of said frame and each comprising a pair of shelling elements mounted on said members, the cup adjacent the flexibly connected ends of the frame members having its shelling elements arranged sufficiently close to receive the tip of an ear of corn, and the shelling elements of the cup located adjacent the handle end of the frame being separated sufficiently to receive the butt of an ear of corn.
2. In a corn sheller, a frame adapted to extend across the open end of a receptacle and provided with pairs of adjustably spaced shelling elements adapted to discharge shelled corn through the frame into the receptacle, and a single adjusting means cooperating with said frame whereby the spacing of the individual elements of each pair may be changed and the spacing of the elements of one of said pairs may be changed to a greater extent than the spacing of the elements of another of said pairs.
3. A corn sheller comprising an angle iron bent to form a U-shaped frame, and shelling elements mounted opposite each other on the respective legs of said frame and presenting tapered concave surfaces to each other, the

axis of said surfaces extending at right angles to the plane of said frame.

4. In a corn sheller, longitudinal frame members flexibly connected at one end, a pair of cooperating shelling elements mounted opposite each other on said members, and a second pair of cooperative shelling elements mounted opposite each other on said members at a point spaced from said first mentioned elements.

5. A corn sheller comprising an angle iron having one flange cut away intermediate the ends of the angle iron and the other flange bent at this point to form a U-shaped frame, and shelling elements mounted opposite each other on said frame and presenting tapered, concave, roughened surfaces towards each other.

6. A corn sheller comprising an angle iron bent into a U-shape, pairs of shelling elements spaced along the straight portions of the angle with the elements of each pair presenting roughened concave surfaces towards each other, and a member extending transversely of the straight portions of the angle and limiting the movement of said elements away from each other.

7. A corn sheller comprising a pair of substantially parallel frame members connected together at one end and spaced apart at the other end, a pair of shellers each comprising a pair of co-operating shelling elements mounted upon said frame members, one of said shellers being located adjacent the connected end of said frame members, and the other of said shellers being located between said first mentioned sheller and the free end of said frame members.

ANDREW E. OLSON.
